Specification for Design.

Patented June 1, 1920.

Application filed October 29, 1919. Serial No. 334,367. Term of patent 3½ years.

To all whom it may concern:

Be it known that I, IRA L. FRENCH, a citizen of the United States, and residing at Chicago, in the county of Cook and State of Illinois, have invented a new, original, and ornamental Design for a Bottle-Stopper, of which the following is a specification, reference being had to the accompanying drawing, forming a part thereof.

Fig. 2 shows a plan view of said bottle stopper.

I claim:

The ornamental design for a bottle stopper, as shown.

In testimony whereof I affix my signature.

IRA L. FRENCH.
